UNITED STATES PATENT OFFICE.

CHARLES F. KELLY, OF PHILADELPHIA, PENNSYLVANIA.

RAILROAD-CROSSING.

1,078,048.

Specification of Letters Patent.

Patented Nov. 11, 1913.

Application filed December 14, 1912. Serial No. 736,693.

To all whom it may concern:

Be it known that I, CHARLES F. KELLY, a citizen of the United States, residing at Philadelphia, in the county of Philadelphia and State of Pennsylvania, have invented 5 certain new and useful Improvements in Railroad-Crossings, of which the following is a specification.

My invention relates to improvements in 10 railroad crossings, the object of the invention being to provide improved mechanism which is controlled by the movement of cars to bridge the gap in the tread portion of the rails where the latter cross, so that the 15 wheels will not bump or jar at the crossing.

A further object is to provide improved mechanism of this character which is controlled automatically by the car approaching the crossing from either direction, and 20 which improvements are of extremely simple construction, strong and durable in use.

With these and other objects in view, the invention consists in certain novel features of construction and combinations and arrangements of parts as will be more fully 25 hereinafter described and pointed out in the claims.

In the accompanying drawings: Figure 1 is a plan view illustrating my improved attachment in full lines and the rails of the 30 crossing in dotted lines. Fig. 2 is a view in section on the line 2—2 of Fig. 1 showing the rails in full lines as well as the attachment. Fig. 3 is a fragmentary view in section 35 on an enlarged scale through one of the corners of the crossing. Fig. 4 is a fragmentary plan view of one corner of the operating mechanism. Fig. 5 is a view in section on the line 5—5 of Fig. 2, and Fig. 6 is a 40 fragmentary view illustrating a detail of construction.

1, 1, represent the rails of a track which cross the rails 2, 2, of a track at right angles to the rails 1. The rails 1 and 2 are illustrated as of the ordinary groove type, and are provided where they cross with gaps which are bridged by my improved blocks 3 movable through openings 4 in the grooves of the rails, and operated by my improved 45 mechanism which will be hereinafter explained. I have illustrated the rails as supported upon bars or ties 5 having platforms 6 affixed thereto, but I would have it understood that the invention is not limited to 50 any particular supporting means, but my improvements may be adapted for use in

connection with various styles of support and incasement to protect the improvements from the weather, and I may resort to other well known expedients in the railroad art 60 to best adapt my improvements for the particular use.

The blocks 3 above referred to are preferably rectangular in form, and are provided at their lower ends with pins 7 which are guided in openings 8 in lugs 9 preferably integral with the rails. These blocks 3 are elevated by wedge blocks 10 secured to bars 11. As seen most clearly in Fig. 1, there are four of these bars 11, and each bar is 70 provided with two wedge blocks, so that when the bars are moved in one direction, the wedge blocks cause their rail blocks 3 to elevate, and when moved in the opposite direction, permit the rail blocks 3 to lower. 75 In Fig. 3, the operation of one of these wedge blocks is illustrated on a somewhat enlarged scale. It will be seen that the wedge block is tapered at one end, but throughout a portion of its length has a 80 straight or horizontal upper surface 12, so that when the rail block 3 is elevated, it will rest upon the horizontal surface 12 and be securely held against downward movement. In other words, this straight surface not 85 only allows a movement of the parts after the block 3 is elevated, but it also prevents the weight of the car on the block from moving the wedge.

At each corner of the crossing, I provide 90 bell-crank-levers 13 which are supported upon the platform 6 above referred to. These bell-crank-levers each consist of a short vertical shaft 14 having two crank arms 15 and 16 secured thereto. These 95 crank arms are connected to bars 26. There are four of these bars 26 located below the bars 11. Each bar 26 is connected with the bar 11 above by means of a lever 27. The levers 27 are fulcrumed between 100 their ends on bolts 28, and at their upper ends extend through openings 29 in bars 11 and have slot and pin connection with said bars. The lower ends of said levers are pivotally connected to the bars 26 as shown 105 at 30, and said levers at their fulcrum points are formed with longitudinal slots 31 in which rollers 32 on the bolts 28 are located, so that friction is reduced to a minimum. It will thus be seen that when the bar 26 110 is moved in one direction, the lever 27 will be swung on its fulcrum to move the bar 11

above in an opposite direction. It will thus be seen that by reason of the bell-crank-levers 13, the bars 26 and the levers 27, the movement of all of the bars are simultaneous. To facilitate this movement with a minimum of friction, I have provided longitudinal slots 17 in the arms of the bell-crank-levers, and through these slots bolts 18 are projected. These bolts 18 extend through the bars 26, and also through metal straps 19 and rollers 20 are provided on the bolts between the straps 19 and the bars. The movement of the bars 26 is controlled by pins 21 which extend through the rails, and are adapted to be engaged by the wheels of a car. These pins are shown located in the tread portion of the rail, but it is of course to be understood that they may be otherwise located and at their bifurcated lower ends they have slot and pin connection with the straddle arms 22 of bell-crank-levers 23, the latter being fulcrumed upon bolts 24 secured in the rails. The other arms 25 of said bell-crank-levers 23 are pivotally connected to the bars 26, so that when the pins 21 are depressed, they cause the bars 26 and 11 to move in a direction to elevate the proper blocks 3 and permit the others to lower. In other words, if the blocks in the crossing grooves are elevated to a point in line with the treads of the rails, the pins 21 in the track will be lowered, but the reverse is also true if the blocks are in a lowered position, the pins 21 will be elevated, so that a car approaching the crossing will first depress pins 21 and through the medium of levers 23, bars 26, levers 14, levers 27 and bars 11, the several wedges 10 will be moved to elevate the proper blocks and permit the others to lower. In other words, the parts are so arranged that when the blocks are raised to bridge the gaps in one track, they are lowered in the grooves of the other track, so that while the wheels of a car pass smoothly over a corner without jolt, they do not come in contact with the blocks in the other track.

While I have illustrated what I believe to be a preferred arrangement of parts, I would have it understood that I do not limit myself to the precise details set forth, but consider myself at liberty to make such changes and alterations as fairly fall within the spirit and scope of the appended claims. Having thus described my invention, what I claim as new and desire to secure by Letters Patent is:

1. The combination with a railroad crossing having openings at the juncture of its crossing rails, vertically movable blocks in said openings adapted to bridge the gap between the rails, horizontally positioned bars below the blocks at right angles to each other, wedges on said bars adapted to move the blocks vertically, said wedges having

straight upper portions upon which the blocks rest when in an elevated position, and means for moving said bars in both directions, substantially as described.

2. The combination with a railroad crossing having openings at the juncture of its crossing rails, vertically movable blocks in said openings adapted to bridge the gap between the rails, horizontally positioned bars below the blocks, wedges on said bars adapted to move the blocks vertically, said wedges having straight upper portions upon which the blocks rest when in an elevated position, lugs on the rails having openings therein, pins on the blocks in said openings in the lugs, and means for moving said bars in both directions, substantially as described. 70 75

3. The combination with a railroad crossing having openings at the juncture of its crossing rails, vertically movable blocks in said openings adapted to bridge the gap between the rails, horizontally positioned bars below the blocks, wedges on said bars adapted to move the blocks vertically, said wedges having straight upper portions upon which the blocks rest when in an elevated position, other bars below the first-mentioned bars, levers fulcrumed between their ends and connecting the respective sets of upper and lower bars, whereby the movement of the latter in one direction causes the movement of the former in the opposite direction, means compelling the lower set of bars to move simultaneously, and means operated by a car for moving said bars, substantially as described. 80 85 90 95

4. The combination with a railroad crossing having openings at the juncture of its crossing rails, vertically movable blocks in said openings adapted to bridge the gap between the rails, horizontally positioned bars below the blocks, wedges on said bars adapted to move the blocks vertically, said wedges having straight upper portions upon which the blocks rest when in an elevated position, lugs on the rails having openings therein, pins on the blocks in said openings in the lugs, other bars below the first-mentioned bars, levers fulcrumed between their ends and connecting the respective sets of upper and lower bars, whereby the movement of the latter in one direction causes the movement of the former in the opposite direction, means compelling the lower set of bars to move simultaneously, and means operated by a car for moving said bars, substantially as described. 100 105 110 115

5. The combination with a railroad crossing having openings at the juncture of its crossing rails, vertically movable blocks in said openings adapted to bridge the gap between the rails, horizontally positioned bars below the blocks, wedges on said bars adapted to move the blocks vertically, said wedges having straight upper portions 120 125 130

upon which the blocks rest when in an elevated position, other bars below the first-mentioned bars, levers fulcrumed between their ends and connecting the respective 5 sets of upper and lower bars, whereby the movement of the latter in one direction causes the movement of the former in the opposite direction, means compelling the lower set of bars to move simultaneously, 10 bell-crank-levers pivotally connected to the rails and connected to the last-mentioned levers, and pins projecting through the treads of the rails and engaging said last-mentioned bell-crank-levers whereby the depression 15 of said pins causes the movement of said blocks, substantially as described.

6. The combination with a railroad crossing having openings at the juncture of its crossing rails, vertically movable blocks in 20 said openings adapted to bridge the gap between the rails, horizontally positioned bars below the blocks, wedges on said bars adapted to move the blocks vertically, said wedges having straight upper portions 25 upon which the blocks rest when in an elevated position, lugs on the rails having openings therein, pins on the blocks in said openings in the lugs, other bars below the first-mentioned bars, levers fulcrumed between 30 their ends and connecting the respective sets of upper and lower bars, whereby the movement of the latter in one direction causes the movement of the former in the opposite direction, means compelling 35 the lower set of bars to move simultaneously, bell-crank-levers pivotally connected to the rails and connected to the last-mentioned levers, and pins projecting through the treads of the rails and engaging said last- 40 mentioned bell-crank-levers, whereby the depression of said pins causes the movement of said blocks, substantially as described.

7. The combination with a railroad crossing having openings at the juncture of its 45 crossing rails, vertically movable blocks in said openings adapted to bridge the gap between the rails, horizontally positioned bars below the blocks, wedges on said bars adapted to move the blocks vertically, said 50 wedges having straight upper portions upon which the blocks rest when in an elevated

position, other bars below the first-mentioned bars, levers fulcrumed between their ends and connecting the respective sets of upper and lower bars, whereby the movement of the latter in one direction causes 55 the movement of the former in the opposite direction, bell-crank-levers at the angles of the crossing having slotted arms, straps on the last-mentioned levers, bolts projected through the last-mentioned levers, through 60 the slots in the bell-crank-lever arms, and through straps, rollers on said bolts between the straps and the last-mentioned bars, and means operated by a car for moving 65 said last-mentioned bars, substantially as described.

8. The combination with a railroad crossing having openings at the juncture of its crossing rails, vertically movable blocks in 70 said openings adapted to bridge the gap between the rails, horizontally positioned bars below the blocks, wedges on said bars adapted to move the blocks vertically, said wedges having straight upper portions upon which the blocks rest when in an elevated 75 position, lugs on the rails having openings therein, pins on the blocks in said openings in the lugs, other bars below the first-mentioned bars, levers fulcrumed between their ends and connecting the respective sets of 80 upper and lower bars, whereby the movement of the latter in one direction causes the movement of the former in the opposite direction, bell-crank-levers at the angles of the crossing having slotted arms, straps on 85 the last-mentioned levers, bolts projected through the last-mentioned levers, through the slots in the bell-crank-lever arms and through the straps, rollers on said bolts between the straps and the last-mentioned bars, 90 and means operated by a car for moving said last-mentioned bars, substantially as described.

In testimony whereof I have signed my name to this specification in the presence 95 of two subscribing witnesses.
